(57) **CLAIM**

The ornamental design for a tire service hammer, as shown and described.

DESCRIPTION

FIG. 1 is a perspective view of a tire service hammer showing an embodiment of our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken line showing of a handle, grooves, and handle openings is directed to aspects of the tire service hammer that form no part of the claim.
